UNITED STATES PATENT OFFICE.

BURT COLIN CAMPBELL, OF CLEVELAND, OHIO.

ELECTRICALLY-OPERATED CLOCK.

Application filed August 21, 1924. Serial No. 733,350.

The objects of the invention are to provide electrically and intermittently operated means for rewinding the actuating spring for the escapement of a clock, thus always 5 keeping the clock in service, and lessening the danger of inaccuracy of movement of regular rewinding, at very short intervals of time.

The invention includes an automatically 10 and electrically wound clock in which a contact member operatively connected with the movement of the escape or second hand wheel closes the circuit to an electrically operated device for revolving the clock 15 train, and through this agency the spring which actuates the escapement of the clock, is periodically rewound at intervals of one minute each.

It includes a resilient actuating spring for 20 revolving the arbor of the second hand wheel and said contact member over the face of a dial, and fixed contact members on said dial bridged by said movable contact member to close an electric circuit leading to said 25 train operating device. The revolvable contact member is adapted to bridge over said fixed contacts once in one complete revolution of the second hand wheel, and the electric circuit is then closed to the mechanism 30 which rewinds the escapement actuating spring previously mentioned.

The escapement spring is thus regularly 35 rewound at intervals of sixty seconds, and in this manner a continuous equal force is exerted on the escape or second hand wheel, causing the pendulum or balance of the 40 clock, to run with undisturbed motion so long as the contact member upon the arbor of the second hand wheel functions to close the electric circuit to the electric operating mechanism or device.

The invention is exemplified in the accompanying drawings, hereinafter more particularly described, and specifically pointed out 45 in the claims.

In the accompanying drawings, Fig. 1 is a front elevation of the clock; Fig. 2 is a side elevation thereof; Fig. 3 is an elevation of the dial on the second hand arbor and 50 the stationary contacts thereon, and circuit closing hand; Fig. 4 is a side elevation of the escape arbor and hub; Fig. 5 includes side and rear elevations of the barrel for the motor spring.

55 In these views, A and B represent the spaced front and rear frame plates of the

clock, connected rigidly together at B'; C is the main arbor mounted in these plates and connected with intervening arbors D and E, by means of the train of gear wheels and pinions F, G, H, I, J and K. K' is the independent arbor of the second hand wheel, K² operated by the resilient driving spring K³ and its barrel K⁴ mounted upon the last pinion K of the clock train, and O is the 60 escapement. The spring K³ operatively connects the arbor K' of the minutes or escape wheel and the pinion K and spring barrel K⁴, so that when the spring is wound up it will revolve the second hand R, preferably 65 made of spring metal for a period of one complete minute, or sixty seconds, about the seconds dial K⁵.

At S and S' are shown spaced contact members on the dial in the path of the second hand R as it revolves about the dial. These are the terminals of an electric circuit T including the electro-magnet U, which, when energized, actuates the gear train to 70 rewind the clock. A metal roller V upon the outer end of the second hand R is raised and drops between and bridges these contacts once in every revolution of the second hand wheel and closes the circuit T leading to the magnet, as the second hand arrives 75 at the 60° point and closes the electric circuit to the magnet.

When energized, the magnet draws forward the armature W, which is provided with the pawl X at its outer end. This pawl 80 engages with the ratchet wheel Y upon the main arbor and turns this arbor and the train of gears through an arc sufficient to 85 rewind the spring until it can carry the escapement through another minute.

A spring W' returns the armature to place when the circuit is broken. A raised member Z upon the dial adjacent to the contacts S, S' elevates the roller and permits it to drop briskly upon the contacts, thus 90 keeping the surfaces of the contacts bright.

The operation of this device equalizes the movements of the escapement mechanism and controls the movements of the clock without producing any strain upon said 95 escapement mechanism, and at the expiration of sixty seconds the hours hand is moved forward and the entire train is set up by the ratchet one minute.

This is accomplished as follows: When at 110 each revolution of the escape or second hand wheel, the electric circuit is closed by bridg-

ing the contacts by means of the second hand, the motor magnet operates to set up the entire train one minute, and rewinds the coiled spring, and gives it power enough to run the escape or second hand wheel for another minute, thus keeping the tension of the spring power upon the arbor of the escape or second hand wheel uniform at all times.

- 10 The escape of the clock functions without, and independent of, any friction or binding attendant upon pivots, train wheels, or any other part of the clock operation. Preferably the coiled spring for the second hand wheel should be overwound at the start, so that it will never become totally unwound, but will exert a constant equable strain upon the escapement. In this manner the whole train stands still, while the 20 escape carries on its undisturbed time keeping action, during each whole minute between the several impulses.

Having described the invention, what I claim as new and desire to secure by Letters 25 Patent is:

1. In an electrically controlled clock, in combination with the arbor of the spring second hand wheel, a spring second hand thereon, a dial therefor, a pinion and barrel, 30 and a coiled spring operatively connecting said barrel and arbor, spaced contact members upon said dial, and a wedge shaped bridging contact member upon said second hand.
- 35 2. In an electrically controlled clock, in combination with the arbor of the second hand wheel, a second hand thereon, a dial therefor, a pinion and barrel, and a coiled spring operatively connecting said barrel 40 and arbor, spaced contact members upon said dial, a wedging roller acting as a bridging contact member therefor on said second hand, a clock gear train for operating said pinion, an hour arbor in said train, hour 45 and minute hands thereon, a ratchet wheel on said arbor, a pawl for operating said arbor, and an electrically operated device for actuating said ratchet on said hour arbor, to advance said minute hand one 50 minute, and set up said train to wind said spring to run the second hand wheel through the space of a minute, and an electric circuit connecting said contacts on said second hand wheel with said electrically operated device.

- 55 3. In an electrically controlled clock, a clock train, an hour arbor and hour and minute hands thereon, a dial therefor, and a separate arbor, a second hand wheel thereon, a pinion in said train, a coiled spring operatively connecting said pinion with the arbor of said second hand wheel, electrically operated means for advancing said hour arbor and minute hand thereon through the 60 space of one minute, a movable contact mem-

ber upon the arbor of said second hand wheel, an electric circuit and terminal contacts therein bridged simultaneously by the wedging action of said movable contact member once in each revolution of said second hand wheel to close the circuit to said electrically operated train advancing means.

4. In an electrically operated clock, a clock train, an electrically operated actuating means therefor, a separate arbor, a second hand wheel thereon, a coiled spring operatively connecting said arbor and train, an electric circuit and spaced contacts in said circuit, a wedge-shaped bridging contact 75 member revolvable with said second hand wheel, and adapted to close said electric circuit once in one revolution of said second hand wheel.

5. In an electrically operated clock, a clock train, electrically and intermittently acting means for operating said train, a separate arbor, a second hand wheel thereon, a spring coil connecting said train and arbor, 90 a second hand on said arbor, a dial therefor, an electric circuit, spaced contacts on said dial for said circuit, and an insulated metal roller having a beveled edge on said hand for bridging said contacts once in each revolution of said hand.

- 95 6. In an electrically operated clock, a second hand wheel, a spring second hand thereon, an insulated contact member on said hand having a beveled edge, spaced contacts in said dial, a projection on said dial adjacent to said contacts, adapted to raise and drop said bridging member upon said spaced contacts once in each revolution of said second hand wheel.

- 100 7. In an electrically operated clock, a second hand wheel, a spring second hand thereon, an insulated contact member on said hand, said contact member comprising a metal roller having a beveled edge, spaced contacts in said dial, a projection on said dial adjacent to said contacts, adapted to raise and drop said bridging member between said spaced contacts once in each revolution of said second hand wheel, a clock train, electric means for intermittently 105 operating said train, and an electric circuit therefor, in which said spaced contacts are situated.

- 110 8. In an electrically operated clock, in combination, an independent second hand wheel and arbor therefor, an insulated hand thereon, a roller mounted upon said hand adjacent to its outer end said roller having a beveled edge and a pair of spaced contacts upon said dial, said roller serving to make wedging contact between said contacts once 115 in each revolution of said second hand wheel, and a projection upon said dial adjacent to said contacts, and positioned in the path of said roller.

9. In an electrically operated clock, a clock train, pawl and ratchet means for operating the same, an electric actuating device for said pawl, an escapement and an escapement wheel and arbor therefor, an operating spring for said escapement wheel arbor, one end of said spring being connected with said arbor, and the other end with a pinion on said clock train, an electric circuit for operating said electric actuating device, and contacts in said circuit closed by the revolution of said escapement wheel arbor once in each revolution thereof to advance said clock train one minute, said 15 clock train also serving to rewind said spring on said escapement wheel arbor.
10. In an electrically operated clock, an escapement and independent escapement wheel, an arbor therefor, an operating spring 20 upon said arbor, means operatively connected with the clock train for rewinding said spring, electrically operated means for advancing said clock train one step for each revolution of said escapement wheel arbor, an electric circuit therefor, and contact members in said circuit closed by the action of said escapement wheel arbor once in one revolution thereof. ²⁵
11. In an electrically operated clock, a clock train, an escapement, and an adjacent escapement wheel and arbor therefor, a second arbor in said clock train in which said escapement wheel arbor is journalled, a pinion thereon, an actuating spring having one end engaged in said escapement wheel arbor, and having the other end engaged in said pinion, pawl and ratchet means for operating said clock train, and electric means for actuating the same, and contacts closed once a minute in said circuit by the operation of said arbor for said escapement wheel. ³⁰
- In testimony whereof, I hereunto set my hand this 26th day of July, 1924. ³⁵

BURT COLIN CAMPBELL.
